UNITED STATES PATENT OFFICE

EDWARD N. JONES, OF PITTSBURGH, PENNSYLVANIA, ASSIGNOR TO THE C. O. BARTLETT & SNOW COMPANY, OF CLEVELAND, OHIO, A CORPORATION OF OHIO

TRUCK FOR TRANSPORTING CONCRETE

Application filed July 14, 1928. Serial No. 292,689.

This invention relates to a vehicular body for transporting and unloading wet concrete, and particularly to a body of this nature which is readily convertible for use in transporting other materials such as sand, gravel, 5 coal, and the like.

During recent years central mixing plants have been established in nearly all large cities in which concrete is mixed, and from which 10 it is transported to the places of its use.

Ordinary dump trucks have been commonly used for such transportation. The disadvantage of such procedure is that it compels the manufacturer of ready mixed concrete to 15 restrict his product to stiff mixes; that is, a mix having a water content so low that it is undesirably harsh and not sufficiently plastic for satisfactory use. This is particularly detrimental when concrete is desired of a 20 consistency permitting it to flow around reinforcing steel.

It is impossible to transport satisfactorily in an ordinary dump truck the wet concrete desired for many purposes, wet concrete being that having a water content sufficiently 25 high as to produce a plastic and workable mixture. When the wet concrete is transported in ordinary dump trucks the mixture segregates; that is, the coarse aggregate gravitates to the bottom, while the grout, composed of sand, cement, and water rises above the coarse aggregate. When the body of the truck is inclined to unload the concrete, the grout containing the most important ingredient, the cement, runs away leaving a portion 30 of the coarse aggregate, stone, slag, or gravel packed in the bottom of the truck. This effect necessitates the use of pointed tools, and great effort, in order to dislodge 40 this packed aggregate. It also necessitates a reconditioning of the concrete, by an additional mixing operation, in order that the concrete may be in proper condition for pouring.

The present invention prevents the sticking 45 of the coarse aggregate to the bottom of the truck, by dumping the load from a collapsible container to the bottom of the truck at the time the concrete is to be unloaded.

50 Tests have shown that the weight of the con-

crete causes the mass to fall when the support of the collapsible container is removed.

Segregation occurs when concrete is transported in any kind of vehicle but by use of means capable of performing a function similar to that of the body described herein. This segregation is corrected when the mass is dropped from the collapsible container to the bottom of the truck. The grout, which has risen to the top during transportation 55 of the wet concrete, is worked back into the mixture through the crater formed in the mass of concrete where it slides to the floor of the truck. When the truck body is inclined for dumping, and the concrete flows 60 out, another remixing and reconditioning process takes place.

Another advantage of the present invention is that the truck body may be readily converted into a form for use in transporting 70 such common materials as coal, coke, sand, gravel, and the like. This saves the purchaser from the expense of maintaining trucks for such general purposes in addition to trucks providing special equipment for the 75 transportation of concrete.

The foregoing objects are obtained by use of the truck shown and described in my co-pending application Serial No. 205,588, filed July 14, 1927. A special object of the present invention also is to provide a truck for concrete of the nature described in which the false sides constituting the concrete containing structure, or hopper, are so arranged that they open automatically under the weight of 80 the material therein.

Another object of the invention is to provide strong and simple means for returning the sides to carrying position after the material therein has been dumped, and to provide means for retarding the separation of the sides under the weight of the material 90 therein.

Another object of the invention is to provide a tail gate for the truck which acts as a 95 chute for delivering material which has been deposited on the floor of the truck.

In the accompanying drawings Figure 1 is a cross sectional view through the body of the truck of the present invention, show- 100

ing the members of the concrete containing structure in raised or carrying position; Figure 2 is a cross sectional view through the body of the truck showing the elements of the concrete containing structure separated and moved into approximately vertical position, to deposit the material carried thereby on the true bottom of the body; Figure 3 is a plan view of the truck body, showing the concrete containing structure in its assembled or carrying position, and showing the tail gate raised to horizontal position, so that it cooperates with the doors to form a chute; Figure 4 is a rear elevation of the chassis and body of the truck, showing particularly the doors and door operating means of the body, means for returning the plates which form the concrete containing structure to their raised or carrying position, and showing the tail gate in dropped or vertical position; Figure 5 is a side elevation of the truck of the present invention, showing the body parts of the truck in carrying position; Figure 6 is a view showing the chassis and associated parts of the truck in side elevation, and the body of the truck in longitudinal section, illustrating the dumping of material from the body; Figure 7 is a detail view, in front elevation, of the means for locking the plate members of the concrete containing structure in carrying position and for controlling their movement into their outer discharging position; Figure 8 is a detail view of the same elements, showing the same in side elevation; Figure 9 is a side elevation of the operating means for moving the elements of the concrete containing structure into their carrying position; Figure 10 is a rear elevation of the elements shown in Figure 9; and Figure 11 is a detail view of the sliding connection of the container members with the upright members of the truck body.

In the accompanying drawings the reference numeral 1 designates the chassis and associated parts of a truck, and the reference numeral 2 designates the true bottom or floor of the truck body, which is arranged to be supported in horizontal position on the chassis or to be tilted into dumping position by any suitable means, those shown being designated generally by the reference numeral 3.

Attached to the true bottom or floor 2 of the body are frame members 4, which may desirably be braced by horizontally extending members 5. The concrete retaining structure of the truck comprises primarily two plates 6 and 7. Adjacent their upper edges, these plates are provided with channeled ribs 8 arranged to embrace bearing members 9 secured to the uprights 4 and extending inwardly of the truck body.

Adjacent the lower edges of the plates 6 and 7 are forked brackets or bearings 10 in which rollers 11 are rotatably mounted.

Pivotedly mounted in other brackets 12, disposed adjacent the lower edges of the plates and having their pivotal centers 13 in longitudinal alignment with the centers of the rollers 11, are curved racks 14. The upper or smooth surface 15 of each of these racks is engaged by a flanged roll 16, which serves to guide the rack during its movement, and to keep its teeth in mesh with those of a pinion 17. Each set of pinions 17 is mounted on a longitudinally extending shaft, two of these shafts 18 and 19 extending along opposite sides of the truck body and having their bearings in angle members 20 carried by the uprights 4.

The means for rotating the shafts 18 and 19 comprise a lever 21 arranged to act on the shaft 19 to rotate the same in either direction. Rotation of shaft 19 is transmitted to the shaft 18 by means of a bevel pinion 22 at the forward extremity of shaft 19 and meshing with a similar pinion 23 on a cross shaft 24. Cross shaft 24 is similarly connected with longitudinal shaft 18 by means of bevel-pinions 25 and 26.

In order to move the plates 6 and 7 into their carrying position, which movement is not resisted by the weight of any material carried thereby, lever 21 is operated to rotate the shafts 19 and 18. The pinions 17 are accordingly rotated, and act on the curved racks 14 to move the same from the position shown in Figure 2 of the drawings to the position shown in Figure 1 thereof. During this action the lower edges of the plates 6 and 7, carried by the rollers 11 which run on the true bottom 2 of the truck, move inwardly toward each other, until they meet adjacent the longitudinal central line of the truck. The upper portions of the plates slide inwardly and downwardly by means of the engagement of channel members 8 with the bearings 9, so that they move from the position shown in Figure 2 to the position shown in Figure 1. It is found necessary to utilize the lever 21 only in starting this movement, as the weight of the plates carries them into position with increased velocity after the movement has been initiated.

When the plates are in this position to form a V-shaped container, their forward and rearward edges abut strips 5^a and 5^b which are attached respectively to a rearward wall 4^a and to a forward wall 4^b of the truck body. These strips prevent the leakage of material past the forward edge of the plates, and thus in cold weather prevent freezing up of plates to the forward and rearward walls of the body.

Means for locking the sides or plates of the container in carrying position comprise a brake drum 27 fixed to the cross shaft 24, and having a brake band 28 thereon. Brake band 28 is connected by a pin 29 and toggle 30 with a locking lever 31 which cooperates

with a ratchet bar 32. When the brake band is locked in tightened position by means of the locking lever 31 and ratchet bar 32, rotation of shaft 24, and consequently that of the shafts 18 and 19 is prevented, and the plates 6 and 7 are locked in position to support the weight of material in the container formed by them.

The rearward end of the truck body is 10 closed by the rear wall 4^a, and by doors 33 and 34, which are hinged on the rear uprights 4 by means of hinge bars 37, and which close the space below the rear wall 4^a. The door 34 of the pair is provided with a vertical bar 15 35, which is arranged to overlap the door 33, and lock the same in position when the doors are closed. The lock for the door 34 comprises a lever 36, which is pivotally mounted in one of the hinge bars 37 of this door. Connected with lever 36 are adjustable rods 38, which are pivotally connected with one leg of each of the bell crank hooks 39 and 40, which are pivoted at 41 and 42 in the hinge bars 37 of the door 34. As shown in Figure 20 4 of the drawings, the bell crank 39 engages in an orifice in a transverse angle member 43, and the hook 40 engages in an orifice in a locking plate 44. In order to unlock the doors, the lever 36 is swung outwardly, that 25 is to the left in Figure 2, and thereby withdraws the hooks 39 and 40 from engagement. In restoring the locking action, the lever is swung inwardly, and the hooks are forced outwardly into contact with the angle member 43 and plate 44 so that they register with and enter their locking orifices.

A discharging platform 45 is hinged to the rearward cross beam 2^a which supports the true floor 2 of the truck body. This platform 30 45 has on its upper surface angularly disposed ribs or bars 46. Chains 47 are fastened to the frame work of the body at the rear thereof, and are provided with hooks arranged to engage the platform 45 when it is 35 brought into a horizontal position.

In order to discharge a load of concrete from the truck, locking lever 31 is operated to release band 28 of brake 27 to the desired extent. As this locking means is released 40 the lower portions of the plates 6 and 7, riding on the rollers 11, separate, and move upwardly and outwardly until they come to rest in the position shown in Figure 2 of the drawings. This action is produced by the 45 weight of the material in the container, without the exertion of any mechanically applied separating force. During this action the concrete in the container falls to the floor or bottom 2 of the truck. During its delivery 50 to the floor 2 the mass of material flows in upon itself, and is thoroughly agitated, thus distributing through the body of the coarser aggregate the grout which has gravitated to the surface of the mass. It is desirable that 55 movement of the plates should not be too

rapid, as a retarded movement produces a better remixing effect. The separating movement of the plates may be regulated by utilizing lever 31 to maintain some pressure of the brake band 28 on the brake 27.

The platform 46, which may remain in its vertical position during the transporting of the material, is raised and supported in horizontal position by means of the chains 47. The locking lever 36 on door 34 is then operated to release the doors. As the body of the truck is tilted into discharging position, as shown in Figure 6 of the drawings, the weight of the concrete on the floor 2 forces the doors 33 and 34 outwardly until they 70 rest against the angularly disposed stop bars 46. This forms a chute with a constricted opening for the final delivery of the concrete from the truck body. Because of this constriction, which causes a crowding of the material being delivered, a final remixing action is obtained, so that the concrete as finally delivered has been thoroughly reconditioned, and may be immediately used without further remixing.

What I claim is:

1. In truck body construction the combination of a floor, and a collapsible body comprising two plate members having their upper portions movably supported and their lower portions arranged to be brought into mutual contact, and means for supporting the plate members on the floor during movement of the plate members.

2. In truck body construction the combination of a floor, a collapsible body comprising two plate members having their upper portions movably supported and their lower portions arranged to be brought into mutual contact, operable means for bringing the lower portions of said plates into mutual contact, and means carried by the plates arranged to contact the floor.

3. In truck body construction the combination of a floor, a collapsible body comprising two plate members having their upper portions movably supported and their lower portions arranged to be brought into mutual contact, means for maintaining the plates in contact, and rollers mounted on the plates and arranged to contact the floor.

4. In truck body construction the combination of a floor, a collapsible body comprising two plate members having their upper portions movably supported and their lower portions arranged to be brought into mutual contact, operable means for bringing the lower portions of said plates into mutual contact, means for maintaining them in contact, and rollers mounted on the plates and arranged to contact the floor.

5. In truck body construction the combination of a floor, and a collapsible body comprising two plate members having their upper portions movably supported and their

lower portions arranged to be brought into mutual contact, said plates being so mounted that they may separate under the weight of material in the container formed by them, and rollers mounted on the plates and arranged to contact the floor.

5 6. In truck body construction the combination of a floor, a collapsible body comprising two plate members having their upper portions movably supported and their lower portions arranged to be brought into mutual contact, said plates being so mounted that they may separate under the weight of material in the container formed by them, and 10 braking means for preventing and retarding separating movement of the plate members.

15 7. In truck body construction the combination of a floor, a collapsible body comprising two plate members having their upper portions movably supported and their lower portions arranged to be brought into mutual contact, said plates being so mounted that they may separate under the weight of material in the container formed by them, braking 20 means for preventing and retarding separating movement of the plate members, and operable means for bringing the lower portions of said plates into mutual contact.

25 8. In truck body construction the combination of a floor, a collapsible body comprising two plate members having their upper portions movably supported and their lower portions arranged to be brought into mutual contact, said plates being so mounted that they separate under the weight of material 30 in the container formed by them, means for supporting the plate members on the floor during movement of the plate members, and braking means for preventing and retarding separating movement of the plate members.

35 9. In truck body construction the combination of a floor, a collapsible body comprising two plate members having their upper portions movably supported and their lower portions arranged to be brought into mutual contact, said plates being so mounted that they separate under the weight of material 40 in the container formed by them, means for supporting the plate members on the floor during movement of the plate members, braking means for preventing and retarding separating movement of the plate members, and operable means for bringing the lower portions of said plates into mutual contact.

45 55 10. In truck body construction the combination of a floor, a collapsible body comprising two plate members having their upper portions movably supported and their lower portions arranged to be brought into mutual contact, and operable means comprising curved racks and operating pinions meshing therewith for bringing the lower portions of said plates into mutual contact.

60 65 11. In truck body construction the combi-

nation of a floor, a collapsible body comprising two plate members having their upper portions movably supported and their lower portions arranged to be brought into mutual contact, operable means comprising curved racks and operating pinions meshing therewith for bringing the lower portions of said plates into mutual contact, and means for maintaining the lower portions of the plate members in mutual contact.

70 12. In truck body construction the combination of a floor, a collapsible body comprising two plate members having their upper portions movably supported and their lower portions arranged to be brought into mutual contact, operable means comprising curved racks and operating pinions meshing therewith for bringing the lower portions of said plates into mutual contact, and braking means for preventing and retarding separating movement of the plate members.

75 13. In truck body construction the combination of a floor, a collapsible body comprising two plate members having their upper portions movably supported and their lower portions arranged to be brought into mutual contact, a tail gate supported from said floor and having a stop member on the upper face thereof, and a door supported from said floor and arranged to cooperate with said stop member to provide a delivery chute.

80 14. In truck body construction the combination of a floor, a collapsible body comprising two plate members having their upper portions movably supported and their lower portions arranged to be brought into mutual contact, operable means for bringing the lower portions of said plates into mutual contact, a tail gate supported from the floor and having a stop member on the upper face thereof, and a door supported from the floor and arranged to cooperate with said stop member to provide a delivery chute.

85 15. In truck body construction the combination of a floor, a collapsible body comprising two plate members having their upper portions movably supported and their lower portions arranged to be brought into mutual contact, means for maintaining the lower portions of the plates in mutual contact, a tail gate supported from the floor and having a stop member on the upper face thereof, and a door supported from the floor and arranged to cooperate with said stop member to provide a delivery chute.

90 100 In witness whereof, I hereunto set my hand.

EDWARD N. JONES.
